UNITED STATES PATENT OFFICE

CARL KRAUCH, OF LUDWIGSHAFEN-ON-THE-RHINE, AND MATHIAS PIER, OF HEIDELBERG, GERMANY, ASSIGNEES, BY MESNE ASSIGNMENTS, TO STANDARD-I. G. COMPANY, OF LINDEN, NEW JERSEY, A CORPORATION OF DELAWARE

CONVERSION OF SOLID FUELS AND PRODUCTS DERIVED THEREFROM OR OTHER MATERIALS INTO VALUABLE LIQUIDS

Application filed February 6, 1926, Serial No. 86,646, and in Germany February 14, 1925.

One of the most important and widely agitated problems in the industrial world has for a long time been how to produce good gasoline or other valuable liquid fuels from solid fuel including coal in all its varieties and wood, and products of distillation, or mineral oils, especially heavy oils.

One attempt at the solution of this problem has been by liquefaction of coals by means of 10 hydrogen or by destructive hydrogenation of tars or oils under high pressure at high temperature, but this has not reached application industrially because of an unsatisfactory speed and rate of the conversion.

By the process herein described we claim 15 to have successfully solved this problem for the first time and to be able to produce good pure liquid fuels, including also benzines from solid fuels and to convert also tars obtained from solid fuels and also heavy mineral oils or residues into more valuable liquid products, including benzines, by a process 20 economical in material, time, labor and wear of apparatus.

In arriving at the herein described process 25 we have made several discoveries or inventions.

We will now set forth a general explanation 30 of our process followed by specific examples thereof with the understanding that the appended claims are intended to cover the features of the invention expressed therein severally and collectively.

We conceived the idea of applying a catalyst 35 to said solid fuel or other materials, in connection with said hydrogenizing high pressure and high temperature process, but found that an improvement of the process 40 could not be obtained at all or at least not in a continued operation.

Thereafter we discovered that the cause of 45 this drawback was the sulfur present in the treated material, and by experimenting discovered certain catalysts which would work satisfactorily under the existing conditions notwithstanding the presence of the sulfur or sulfur compounds. Such catalysts prove valuable not only under high pressure but even 50 under ordinary pressure, though high pressure is more suitable, and most advanta-

geously the hydrogenizing gas is employed in the form of a stream.

Thereupon we found that the apparatus 55 were attacked too rapidly for industrial success due to several influences, chiefly to the presence of sulfur mostly found in the starting materials, and that many troubles in the operation and also other drawbacks were hereby caused, and we discovered that under 60 the conditions existing in the process of hydrogenizing, whether with an addition of the aforementioned or other catalysts or in the absence of catalysts an apparatus composed of or lined with aluminium would behave excellently. Even with materials rich in sulfur, for example Mexican Panuco oil, aluminium or its alloys are not attacked by the contact with hot, gaseous, liquid or solid material, and when using them as a lining they 65 may be used until near their melting point. 70 Also chromium and alloys therewith prove resistant to the attack in the course of the operation in so far as these metals or their alloys are impermeable to gas and do not contain free injurious iron. Especially chromium itself and alloys containing more than 75 10 per cent of chromium and not more than 0.2 per cent, preferably less than 0.1 per cent of carbon, are very suitable. At the same time a content of nickel amounting to 40 80 per cent or more makes a very useful material which is not attacked even if in use for a very long time.

We further discovered that the process according to the present invention is in many 85 cases, and in particular when converting solid fuels or heavy oils or residues, greatly improved by carrying out the process in two parts or stages. In the first stage the coal, 90 tars or heavy petroleum products are converted into liquids poor in fractions of low boiling point by liquefaction or destructive hydrogenation with or without catalysts, while in the second stage the products of stage one are 95 transformed into hydrocarbons of low boiling point, by destructive hydrogenation, but preferably with the aid of catalysts. Increased pressure is preferably employed in one or both stages. Insofar as catalytic masses are 100 added in both stages, they may be of the same

kind or different in quantity, concentration, or kind. The two stages can be effected in two separate or adjoining reaction vessels or in different parts of a single vessel constructed in a suitable manner. Even more than two stages may be employed successively in certain cases.

The catalysts most suitable to be added for effecting the said conversion must be of a nature substantially immune to sulfur poisoning in this process and can be of varied character. As examples we quote compounds of nitrogen, or combined sulfur, particularly sulfids of heavy metals, also molybdenum, tungsten, chromium and uranium which are here referred to as metals of the sixth group of the periodic system or compounds of such metals. Other catalysts immune from sulfur poisoning may also be used or more than one such catalyst at the same time or successively, or mixtures of such catalysts with other bodies. Other compounds acting in a different way, for example, as splitting agents, and inert solid bodies may also be added.

As examples of compounds of nitrogen to be added to the materials which are to be brought into reaction, we mention ammonia, or ammonium sulfid, or nitrides, for example silicon or titanium nitrides which are comparatively stable to water. Several compounds of nitrogen of different character, for example solid and gaseous compounds as nitrides and ammonia may be used at the same time. Instead of nitrogen compounds, free nitrogen may be added to the hydrogen gas in the presence or with an addition of catalysts capable of synthesizing ammonia, but ammonia or other compounds of nitrogen may also be added simultaneously.

When employing combined sulfur, it may be added in different forms, for example of sulfides, single or mixed, also in mixture with metals, such as silver, molybdenum, tungsten or cobalt or oxids, such as those of magnesium, calcium, zinc, aluminium, titanium, zirconium, cerium, thorium, vanadium, chromium, molybdenum, tungsten, uranium, manganese or cobalt or hydroxids such as those of calcium, aluminium, thorium, chromium, manganese or cobalt or carbonates such as those of lithium, beryllium, magnesium, calcium, zinc, manganese or cobalt and the like, especially in mixture with catalysts promoting hydrogenation. Sulfids of heavy metals, particularly those of the iron group, whether alone or in mixtures, are of special efficiency. Sulfur may also be introduced in other forms, for example by adding sulfites or sulfates, or adding free sulfur to metal oxids such as those of zinc, vanadium, molybdenum, tungsten, uranium, manganese or cobalt and the like and thereby generating a catalyst containing combined sulfur. Also by treating iron with sulfuretted hydrogen or oils obtained by pressure hydrogenation

at an elevated temperature a catalyst of lasting efficiency can be produced.

When using metals of the sixth group of the periodic system or compounds thereof as catalysts, the latter may comprise, for example, molybdenum or other related metal as free metals or compounds, such as sulfids, or molybdic acid, or ammonium molybdate, and these substances may be employed either alone or in mixture with other bodies which may possess hydrogenating properties, or not. For example, cobalt or iron, or compounds thereof, or alumina, zinc oxid, magnesia, or calcium carbonate may be cited as additions to the said catalyst immune to sulfur poisoning. The said catalysts may be employed on supports such as lumps of clay.

We cite as further examples of catalysts immune to sulfur poisoning adapted to be used in this process, compounds of silver, copper, cadmium, lead, bismuth and tin, lithium oxid or carbonate, magnesite, boric acid, alumina, rare earths, difficultly reducible oxids of the metals of the fourth group, oxids or carbonates of zinc, manganese and vanadium, difficultly reducible oxids of other metals, and combinations of two or more of the above mentioned metals, as such, or in the form of their compounds, for example, a mixture of copper and zinc or a mixture of silver and chromium or a mixture of compounds of said metals with or without additional catalytic elements, especially iron or other metals of the iron group. Generally catalysts suitable to give rise to methanol from hydrogen and an oxid of carbon can be employed, and is is preferable in such cases to employ mixtures of hydrogen and an oxid of carbon or to use steam.

The said catalysts may be added in any suitable manner. They may be added to the solid or liquid material, or in the case of liquids they may be placed into the reaction vessel and the liquids brought into contact with them in a vaporized or otherwise finely divided state. Other bodies, for example, lumps of brick, quartz, asbestos, coke, active carbon, silica gel, metals, especially heavy metals, or metal oxids, or carbides, or mixtures of such bodies, may also be present in the reaction chamber. The said bodies have the effect of avoiding the formation of carbon deposits and of facilitating the distribution of the hydrogenating gas.

As regards the materials to be treated, the invention can be applied to any sort of solid fuels, for example, hard or soft coal, brown coal, lignite, peat, wood, or similar materials, mineral oils, shale oils, or other solid or liquid bitumina, also distillation or extraction products of all of them, such as tars obtained from them, whether by ordinary destructive distillation or by low temperature carbonization, or brown coal bitumen, or tars

of solid or liquid fuels, or components or conversion products of all above mentioned materials, such as cracked products, coumarone or any other resins or residues of their distillation, pitch, asphaltum and so on, or mixtures of several such products with each other, also of solids with the above named liquids or of one or more of such products with other suitable organic liquids.

Especially when employing coal or liquid fuels, an addition of lignite or peat is often of advantage, often increasing the hydrogenizing action, avoiding several drawbacks and in the case of solid substances rendering their introduction easier. All the said materials may be used in the presence of substantial amounts of water and, if desired, water may be added as such. Sometimes the process of hydrogenation is hereby furthered. For example lignite producer tar containing from 40 to 50 per cent of water may be used to advantage directly.

The preferred form of carrying out the process is generally a continuous operation with a stream of the gases and with an excess thereof over the required quantity and preferably while maintaining the desired pressure by adding fresh gas and passing the gas either by circulation through one or more reaction vessels or through a succession of several reaction vessels. The material to be converted is supplied at the proper place and the products are separated from the reaction gases by cooling.

The gases serving for the reaction may consist of hydrogen alone or of mixtures containing hydrogen, for example a mixture of hydrogen with nitrogen, or water gas, or hydrogen mixed with carbon dioxid, hydrogen sulphide, water vapor or methane or other hydrocarbons. Or the hydrogen may be generated in the reaction chamber by the interaction of water and carbon monoxid, and the like. When employing nitrogen, compounds as catalysts, and carbon monoxid and water, the gas must be employed in a stream.

The hydrogen gases required for the destructive hydrogenation can be obtained in any suitable manner; among other methods the following may be mentioned.

Gaseous or vaporized hydrocarbons, whether alone or mixed with each other or other gases are decomposed at a high temperature with a suitably restricted quantity of oxygen or a gas rich in oxygen so as to combine substantially only the carbon contents with oxygen producing carbon monoxid and setting free the hydrogen. Water vapor or carbon dioxid or both may be added to the oxygen and catalysts may be employed in order to facilitate the partial combustion, for example nickel coated magnesia or other solid bodies, or fused iron or iron alloys. The carbon monoxid may thereupon, when found

desirable, be catalytically brought into reaction with steam in order to produce more hydrogen. As in the process of liquefaction or destructive hydrogenation of coal and other materials, methane and other simple hydrocarbons are produced, the gases obtained in the reaction or the hydrocarbons isolated therefrom may serve for the said decompositon, preferably after the more valuable higher gaseous hydrocarbons, for example ethane or propane, have been removed by means of cooling or suitable absorbents and recovered for other uses. The decomposition with oxygen may also be effected at an elevated pressure with special advantage when making use of the gases resulting from the hydrogenation process, in which case the decomposition may be effected at a pressure identical with or lower than that prevailing in the hydrogenation in order to save compression energy.

The process is best carried out under elevated or even strongly elevated pressure and most suitably with a stream of the gas passed through or over the material to be treated or carrying it along through the reaction vessel by which method the production obtained by the process is very large.

Depending on the condition of working, for example temperature and pressure employed or duration of the treatment, the products are poor or rich in products of low boiling point. Generally the temperature ranges between 300 and 700 degrees centigrade, and when working under pressure, it should amount to 20, 50 or more atmospheres.

Compounds obtained by the aforescribed hydrogenation treatment of solid fuels, tars, mineral oils and other materials referred to, which compounds may be comprised by the term destructively hydrogenized fuels are generally very low in sulfur or even completely free therefrom and are excellently suitable for use as fuel for internal combustion engines. These destructively hydrogenized fuels, whether obtained as aforescribed or otherwise, may be mixed with one or more other liquid fuels, for example, benzines or gasoline obtained by the cracking process, benzol or low alcohols of the aliphatic series and possess the remarkable property of being miscible with the latter, particularly with methanol, to a large degree. Such mixtures are also useful as fuels for internal combustion engines. A mixture composed of 60 per cent, by weight, of a hydrocarbon obtained from lignite, 30 per cent of gasoline and 10 per cent of methanol may be cited as an example. The destructively hydrogenized fuels, however produced, are also valuable as solvents for various purposes for which they may be used either alone or in conjunction with other bodies.

They excel by being miscible with

many bodies. With many such bodies natural benzines would mix only to an unsatisfactory or very restricted degree. For example, methanol or aqueous alcohol can be mixed to a large extent or even in any proportion with the synthetic benzines. They are also excellent solvents for many purposes.

In the accompanying drawings, an apparatus for carrying out the one stage process 10 and an apparatus for carrying out the two stage process, both being continuous, are illustrated diagrammatically, partly in vertical section. Our invention is not limited to the apparatus illustrated therein, however; 15 but may be varied at will in accordance with the conditions of working.

Referring to the drawings in Fig. 1 in detail, reference numeral 1 indicates a feed line from any convenient source of liquid 20 raw material. The line 1 discharges to a grinding mechanism 2 fitted with a hopper 3 through which solid materials may be admitted. If desired, the grinding mechanism can be by-passed by line 1a when no solid 25 materials are used. The suspension of solid material in liquid or the liquid alone may be then forced by pump 5 through a line 4 to a heat exchanger 6 and thence by line 7 into a reaction chamber 8. The reaction 30 chamber is constructed in any preferred manner and should be adapted to withstand high pressures, for example; above 20-100 or even as high as 800 atmospheres, as well as the 35 corrosive effects of the reactants. The vessel is preferably protected from loss of heat by a suitable insulating cover 9 and may be heated by electric coils 10 which are arranged within the drum. The contents of the drum are preferably kept in a state of agitation 40 by means of a stirring mechanism 11 and, if desired, suitable catalytic materials 11' as indicated above may be attached to the stirring mechanism so that the catalyst is brought into intimate contact with the contents of 45 the vessel.

Hydrogen under high pressure is forced through a line 12, heat exchanger 13 and then by line 14 into the base of the reactor 8 into which it is preferably discharged through a 50 spray pipe 15. A liquid level may be maintained in the drum, for example at the point 16a and gas and vaporous products may be continuously withdrawn by vapor line 16 which is in communication with exchanger 55 13 and a cooling coil or condenser 17. The condensate and gas is discharged into a separation drum 18 from which the distillate is removed by line 19 to storage, not shown. The gas may be taken off by a pipe 20 to a 60 purifying system indicated at 21, and which may comprise a scrubbing system preferably carried out at high pressure using, for example, soda to remove hydrogen sulfide and oil to remove hydrocarbon constituents from the gas. Purified gas is then recompressed 65

by a booster pump 22 and is forced again into the hydrogen feed line 12. Fresh hydrogen may be introduced by line 23. If desired, oil may be continuously removed from the drum by a line 24 which communicates with heat exchanger 6 and which is withdrawn to storage, not shown, by a suitable line 25.

Referring now to the drawings in Fig. 2 a suitable system is shown for converting 75 solid materials into light liquid oils by two steps. Where possible, the same numeral has been used in Fig. 2 as has already been indicated in Fig. 1. Hydrocarbon oil is withdrawn from any suitable storage, not shown, 80 by a line 1 and may be forced through a grinding mechanism 2 which is fitted with the hopper 3 for the introduction of solid material, such as coal, lignite or the like. The pump 5 forces this mixture through line 4 into the first oven indicated by the numeral 8a. This oven may be constructed in the same manner as the oven 8 shown in Fig. 1 and similar parts are designated by the same numerals. A heavy liquefied material is withdrawn from the base of the oven 8a and may be continuously discharged into the second oven indicated by 8b. This oven may be packed with a suitable solid catalytic material indicated at 11' and with the exception 90 that no stirring mechanism is used it may be constructed similarly to oven 8a.

Hydrogen is forced under high pressure from the line 12, as before, through a heat exchanger 13 and by line 14 and branches 100 14a and 14b into oven 8a and 8b respectively. Vaporous products and gas are removed from both ovens by vapor line 16a and 16b respectively which may discharge through a single exchanger 13 to condenser 17. The light oils are separated from the gases in the separator 18 from which the oil is removed by 19 and the gases may be removed, purified and recompressed as indicated in Fig. 1. Heavy oil may be continuously withdrawn 110 from the oven 8b and a part or the whole thereof may be continuously discharged through a line 24a, cooler 26 and conducted by line 25 to any suitable storage. If desired, a part of this oil may be re-circulated to line 115 1 or to line 4 by means of recirculation line 24b, pump 27 and either of the two lines 28 or 29, as is desired.

In the operation of this system solid carbonaceous material containing ash may be 120 continuously fed to the first oven and a sufficient quantity of the oil containing inorganic material may be led from the system by the lines 24a and 25 so as to prevent accumulation within the system. Fresh hydrocarbon oil may be continuously fed in sufficient quantity to carry in the solid material or if desired, a part of the oil withdrawn from the second oven, either containing ash 125 or from which the ash has been removed by

filtration, settling centrifugal means or the like may be recirculated for the purpose of bringing in the fresh solid material.

In the following examples the time of reaction varies considerably, as might be supposed, depending on the nature of the raw material, the activity of the catalyst, temperature, pressure and the like. In practice it is desirable to make a few preliminary runs in order to determine the time required for the best yields under a given set of conditions. Generally speaking, with batch operations the total time may be from two to ten hours or more, depending on the yield desired, while with continuous operations the time is usually shorter. When continually feeding liquid or difficultly vaporizable oils, the rate of flow may be in the neighborhood of .3 to .8 volumes of oil per hour per volume of reaction space. Vaporous materials may be treated at higher temperatures and the feed rate may consequently be one or even one and one-half volumes per hour per volume of reaction space. The volume of hydrogen may likewise vary considerably and should always, of course, be in excess of that actually required for the conversion; for example, the rate of flow of hydrogen may be in excess of about 600 litres per kilogram of carbonaceous material.

The following examples will serve to further explain how our invention is carried out in practice, but we do not restrict our invention to these examples.

Example 1

Brown coal dried in the air is introduced in a continuous manner into a vessel capable of withstanding high pressure and heated to about 500 degrees centigrade and exposed therein to the action of a stream of hydrogen in excess of the required amount and brought under a pressure of 100 atmospheres, after an addition has been made to the gas of 1 per cent by volume, of ammonia. The products of the reaction are carried away with the gas current and condense by cooling after leaving the furnace, whereby a thin oil with but little phenolic bodies is obtained. In the end 80 per cent or more of the carbonaceous matter contained in the brown coal is liquefied and at the same time 10 per cent of gaseous hydrocarbons are formed.

The conditions of working may be varied to a large extent; the pressure may be lower or higher. In addition to ammonia other catalysts, or solid bodies may be employed, for example, iron, cobalt, or the like, or porous lumps of clay, adding them to the coal or arranging them separately. The brown coal may be mixed with a liquid, for example, with part of the product obtained as described.

Example 2

A vessel suitable to withstand high pressure is supplied with pieces of pressed aluminium hydroxide and heated to about 500 degrees centigrade and a gas mixture composed of 79 per cent, by volume, of hydrogen, 20 per cent of nitrogen and 1 per cent of ammonia, charged with the vapors of dehydrated brown coal producer tar at a low partial pressure is led through under a pressure of 200 atmospheres. On cooling the gases leaving the vessel, a product containing thin liquid hydrocarbons is obtained, which is practically free from oxygenated and unsaturated compounds. The residual gas mixture may be returned to the reaction vessel after replacing the consumed hydrogen and removing gaseous hydrocarbons which are formed to a small extent.

When employing titanium nitrid instead of ammonia and aluminium hydroxide, and the above gas mixture or hydrogen alone, under similar conditions, a product containing about 70 per cent its weight of gasoline boiling up to 200 degrees centigrade is obtained.

Mixtures of coals and tars or of coal or tar with products of the hydrogenation of such materials or with other suitable liquid diluents may also be employed.

Example 3

Raw cresylic acid obtained from coal tar is passed with a current of hydrogen under a pressure of 150 atmospheres and at a temperature of from 380 degrees to 400 degrees centigrade over a catalyst obtained by pressing precipitated cobalt sulfid into lumps. The reaction sets in vigorously after a short while and proceeds at a constant velocity. In the product obtained by cooling, the phenols are largely reduced to hydrocarbons.

Similarly, when treating coal tar or brown coal tar or raw distillates thereof, phenolic bodies contained therein are reduced to hydrocarbons to a satisfactory degree notwithstanding the presence of hydrocarbons and impurities such as sulfur compounds, pyridine and the like; unsaturated compounds are converted into saturated ones, mobile valuable oils being thus formed in a continuous operation without formation of asphaltum or coke.

In the above example, cobalt sulfid may be replaced by a mixture of the sulfids of cobalt and nickel, or of cobalt and manganese, or of cobalt and iron, or by zinc sulfid or aluminium sulfid, or other catalysts containing combined sulfur.

Example 4

Brown coal is intimately mixed with 1 per cent its weight of molybdic acid and introduced into a vessel capable of withstanding high pressure, in which it is treated at about 130

500 degrees centigrade and under a pressure of 150 atmospheres with a steam of hydrogen. The coal is soon and easily completely transformed into valuable thin hydrocarbons.

5 *Example 5*

Brown coal tar obtained in a gas producer fed with brown coal, is vaporized at a temperature of 500 degrees centigrade and under 10 a pressure of about 150 atmospheres, in a current of hydrogen, and the mixture is continuously passed over a contact mass consisting of a mixture of molybdic acid with an addition of 20 per cent its weight of aluminium 15 hydroxide. The gas is pumped round in a circular way while maintaining the pressure by an addition of fresh hydrogen, and separating the material by cooling. There is formed a mobile and nearly colorless product 20 free from phenols, without any formation of coke, asphalt or other residue. From thirty to fifty per cent of the product distil up to 150 degrees centigrade, and the fractions up to 300 degrees centigrade are colorless and 25 fully saturated. At 350 degrees centigrade only a small residue is left having a vaseline-like nature. The raw product can be used as a motor fuel or for manufacturing lubricating oils. An addition of say 1 per cent of 30 ammonia to the hydrogen is also useful.

A mixture consisting of 75 per cent, by volume, of hydrogen and 25 per cent of nitrogen may also be used, preferably at a pressure of 200 atmospheres.

35 Molybdic acid alone or molybdenum sulfid or other masses containing molybdenum may also be employed, also coal tar, and components such as raw cresylic acid.

40 *Example 6*

Raw cresylic acid obtained from coal tar is passed along with a current of hydrogen over tungstic acid under a pressure of 50 atmospheres and at a temperature of about 500 45 degrees to 550 degrees centigrade whereby it is rapidly and completely converted into hydrocarbons.

40 *Example 7*

50 Petroleum residues when treated as described in the foregoing example yield in a continuous manner and without any formation of coke or asphaltum, at between 450 degrees and 500 degrees centigrade, a product 55 containing from 50 to 80 per cent of benzene boiling up to 150 degrees.

40 *Example 8*

Brown coal tar obtained in a gas producer 60 is continually passed, along with a mixture of 3 parts of hydrogen with 1 part (by volume) of nitrogen at about 500 degrees centigrade and under 200 atmospheres over a catalyst consisting of chromium hydroxid. The tar 65 is hereby converted into a mobile oil, prac-

tically free from phenol and of a saturated nature and containing about 50 per cent of benzine (boiling up to 150 degrees centigrade). The fractions of higher boiling point are free from asphaltum and can be converted 70 into benzine by a repeated treatment.

70 *Example 9*

Lignite, whether alone or mixed with mineral or tar oil, is continuously fed into a high 75 pressure reaction vessel in which it is exposed to the action of a current of hydrogen in excess of the consumed quantity under a pressure of 200 atmospheres and at a temperature of about 480 degrees, while the solid or pasted material is slowly moved forward through the reaction vessel. The hot gas current containing the products formed by the interaction with hydrogen is passed into a second reaction vessel also capable of withstanding the 80 pressure, which latter is maintained and which vessel is supplied with precipitated calcium carbonate in lumps and heated to from 500 degrees to 550 degrees centigrade whereupon the gases are cooled after having transferred heat to the gas entering the first vessel; a mobile oil collects in the cool receiver containing about 50 per cent, of benzine of low boiling point. The gas is freed from 85 gaseous hydrocarbons which are present in a small amount and is then passed with an addition of fresh hydrogen to make up for the consumed amount thereof, by means of a circulating pump, successively through the first and second vessel and the cooler and so forth. 90 The solid residue, chiefly ashes, left by the treatment of the brown coal is suitably withdrawn between the first and second vessel. By this treatment 70 or more per cent of the carbon 95 contents of the lignite is easily and quickly converted in a continuous manner into valuable hydrocarbons.

A catalyst of the character described above may also be employed in the first stage, and in the second stage the calcium carbonate may be replaced by other such catalysts and those of a more precious character are preferably employed in the second stage where there are no ashes or other solid residues.

100 *Example 10*

Dark colored residues of an American rock oil which at ordinary temperature are nearly solid and have a strongly unsaturated character are incorporated with an excess of a gas mixture composed of three parts, by volume, of hydrogen and 1 part of nitrogen and continuously passed under a pressure of 105 200 atmospheres and a temperature of from 450 degrees to 500 degrees centigrade over a catalyst prepared from an intimate mixture of 70 parts, by weight, of ammonium molybdate and 30 parts of aluminium hydroxid. A nearly colorless, mobile and saturated product is obtained besides a little methane,

consisting of 90 per cent of colorless petrol boiling up to 150 degrees and 10 per cent of a thin, yellowish product of a higher boiling point.

Example 11

Jura shale oil of 0.950 sp. gr. containing 4 per cent of sulfur which on distilling yields 6 per cent petrol up to 150 degrees and 21 per cent of a pitch-like residue over 350 degrees centigrade is treated as described in the foregoing example. The product is a mobile yellowish oil of 0.810 sp. gr. containing 80 per cent of saturated petrol boiling up to 150 degrees and leaving at 200 degrees centigrade a liquid only slightly colored residue.

Example 12

Mexican asphaltum is dissolved in its own weight of cyclohexane and treated in the aforescribed manner. The cyclohexane is recovered unaltered, while the asphaltum which before the treatment contained 4 per cent compounds boiling up to 250 degrees centigrade, 25 per cent more boiling up to 350 degrees centigrade and 70 per cent of a hard pitch residue is converted into a mobile oil, free from oxygen compounds and chiefly consisting of petrol hydrocarbons besides a very small vaseline-like residue.

Rock oils of any origin may be treated as described in the above examples and thereby converted into refined products of much more valuable properties.

Example 13

Dark-colored residues of an American rock oil which at ordinary temperature are nearly solid and have a strongly unsaturated character, are incorporated with an excess of a gas mixture composed of 3 parts, by volume, of hydrogen and 1 part of nitrogen, with or without an addition of free ammonia, and passed in a continuous manner over an activated iron catalyst as suggested for the synthesis of ammonia, at a pressure of 200 atmospheres and a temperature of from 450 degrees to 500 degrees centigrade. The product which is formed besides a little methane is a slightly yellowish liquid of 0.800 or less sp. gr. which on distillation yields about 50 per cent of gasoline boiling up to 150 degrees centigrade of saturated character, up to 250 degrees centigrade additional 28 per cent distillate and leaves at 325 degrees centigrade about 5 per cent of a thick or vaseline like only slightly colored residue.

With silicon or titanium nitrid instead of activated iron and the above gas mixture or pure hydrogen a similar result is obtained.

Example 14

Dark-colored residues of an American rock oil which at ordinary temperature are nearly solid and have a strongly unsaturated char-

acter, are incorporated with hydrogen and passed continuously under a pressure of 200 atmospheres and at from 450 degrees to 500 degrees centigrade over a catalyst prepared by forming precipitated cobalt sulfid. A light-colored, thin liquid is produced besides a little methane which on distillation yields 50 per cent of a fraction up to 150 degrees and additional 35 per cent up to 350 degrees centigrade, all of a saturated character. The small residues are thick or vaseline-like and free of pitch.

Example 15

Steamer fuel oil, produced from American oil, is passed in a continuous manner, together with a mixture of hydrogen and nitrogen, at about 500 degrees centigrade and under a pressure of 200 atmospheres over a catalyst prepared by impregnating porous material with lead nitrate. The gas is circulated while maintaining the pressure and making up for the consumed hydrogen by fresh gas. A light-colored product of 0.85 sp. gr. is produced, the lower fractions of which may directly serve as a fuel for internal combustion engines, while the higher fractions are a high-grade starting material for preparing lubricating oil.

Instead of lead nitrate, stannous chlorid, silver nitrate, cupric hydroxid and others, whether single or mixed with each other or with compounds of iron, cobalt and others, may also be used, and other materials such as tars, coal, etc. may be treated in a similar way.

Example 16

Cresylic acid obtained from coal tar is continuously passed along with a mixture of hydrogen and nitrogen at about 450 degrees centigrade and under a pressure of about 150 atmospheres over a catalyst containing the oxids of silver and titanium. The phenolic bodies are hereby completely reduced to hydrocarbons. Catalysts comprising lithium carbonate, magnesite, manganese oxid, silver borate, or copper and cerium oxid, or silver and cobalt oxid can be used similarly.

Example 17

Brown coal producer tar is continuously passed together with a current of hydrogen, under a pressure of 800 atmospheres and at a temperature of about 500 degrees centigrade over a catalyst consisting of porous material coated with vanadic acid. The product obtained consists of up to 50 per cent of gasoline.

A catalyst containing thoria or a mixture of compounds of uranium and zinc or of copper and zinc or of silver and tungsten or of silver and silicon or others with or without a carrier may also be used.

Example 18

Two parts of lignite producer tar are mixed with 1 part (by weight) of raw lignite or peat and continuously forced into a high pressure vessel and treated therein with hydrogen under a pressure of 200 atmospheres and at about 450 degrees centigrade or higher, but not exceeding 600 degrees centigrade 5 while providing for an intimate contact of gas and material by employing a rapid current of gas, stirring or the like. The gas mixture leaving the vessel is cooled by exchange of heat with the freshly entering 10 gases. A thin hydrocarbon product with about 25 per cent of a gasoline fraction is obtained, the high boiling fractions of which may be subjected to a repeated treatment or utilized in any other manner, for example 15 for the production of lubricating oils or solvents or washing means or impregnating oils or insulating oils. The hydrogen is pumped around while the residue containing ashes and mostly a little carbon is slowly discharged 20 as a paste. The gas current may be so rapid that the gases of the reaction carry enough 25 of the products to be subjected to a second or even third or more treatments in subsequent vessels. If in the second vessel a 30 catalyst containing molybdenum is employed, over which the reaction gases pass at about 500 degrees centigrade, a product with 50 per cent of a petrol fraction is readily obtained with a complete reduction of phenolic 35 bodies and an extensive removal of sulfur.

An addition may be made to the starting material of roasted pyrites or other contact bodies.

Example 19

40 Vaporized brown coal tar is incorporated with a gas mixture composed of 10 per cent, by volume, of carbon monoxid and 90 per cent of hydrogen and brought under a pressure of 200 atmospheres, and the mixture is passed at about 450 degrees centigrade over a catalyst suitable for the synthesis of methanol prepared from 9 parts of zinc oxid and 1 part of chromic acid. On cooling, a product 45 is condensed which contains some methanol and oxygen compounds of a higher order, about 30 per cent of benzine and products of a higher boiling point which may serve for a conversion into lubricating oils or for a repeated treatment as aforementioned. The mixture of hydrogen and carbon monoxid is circulated while replacing the consumed 50 gases.

In all of the above examples the hot parts 60 of the apparatus may be lined or coated with aluminium or aluminium alloys or chromium or made or coated with an alloy of 60 per cent of nickel, 27.7 per cent of iron, 12 per cent of chromium and 0.3 per cent of carbon; or an 65 alloy composed of 58 per cent of nickel, 25

per cent of iron, 17 per cent of chromium and 0.03 per cent of carbon; or an alloy composed of 96 per cent of iron, 1.75 per cent of nickel, 1.5 per cent of chrominum, 0.1 per cent of carbon and also of 0.25 per cent of silicon, 70 0.27 per cent of manganese, besides small quantities of copper, sulfur and phosphorus.

Our invention is not confined to the above examples; the conditions may be widely varied in various directions. For example the 75 pressures and temperatures may be higher or lower than stated above.

In the appended claims, the expression "distillation and extraction products thereof" is intended to relate only to normally 80 solid and liquid distillation and extraction products and is not to be construed to include normally gaseous products of the distillation of solid and liquid fuels.

Likewise when the expression "containing 85 a metal of the sixth group" is used it is intended to mean such metals in the free and in the combined state.

Also when the expression "added catalyst" is used in said claims it is not necessarily intended to mean that a catalyst is introduced into the reaction chamber with each charge of carbonaceous material but is merely intended to indicate that the reaction is carried out in the presence of an effective quantity of 90 a catalytic material which is not naturally contained in the carbonaceous material undergoing treatment or is contained in said carbonaceous material in ineffective quantities. 95

What we claim is:—

1. The process of destructively hydrogenizing carbonaceous substances, such as solid and liquid fuels, distillation and extraction products thereof, into valuable liquids which comprises treating them with added hydrogen in the presence of an added catalyst immune to sulfur poisoning, and heat at a temperature sufficient to promote the conversion and at a pressure of at least 20 atmospheres. 100

2. The process of destructively hydrogenizing carbonaceous substances, such as solid and liquid fuels, distillation and extraction products thereof, into valuable liquids which comprises treating them with added hydrogen in the presence of an added solid catalyst immune to sulfur poisoning, and heat at a temperature sufficient to promote the conversion, and at a pressure of at least 20 atmospheres, the conditions of working, such as 110 temperature, pressure, and the efficiency of the catalyst being so adapted to each other, as to give rise to the formation of substantial amounts of low boiling hydrocarbons of a benzine character. 120

3. The process of destructively hydrogenizing carbonaceous substances, such as solid and liquid fuels, distillation and extraction products thereof, into valuable liquids which comprises treating them with a stream of hy- 125 130

- drogen in the presence of an added catalyst immune to sulfur poisoning and heat at a temperature sufficient to promote the conversion and at a pressure of at least 20 atmospheres.
4. The process of converting carbonaceous substances, such as solid and liquid fuels, distillation and extraction products thereof, into valuable liquids by destructive hydrogenation which comprises treating them with hydrogen and a catalyst containing molybdenum at a temperature upwards of 350° C.
5. The process of destructively hydrogenizing carbonaceous substances, such as solid and liquid fuels, distillation and extraction products thereof, into valuable liquids which comprises treating them with added hydrogen, and a catalyst containing a metal of the sixth group of the periodic system, and heat at a temperature sufficient to promote the conversion and elevated pressure of at least 20 atmospheres.
6. The process of destructively hydrogenizing carbonaceous substances, such as solid and liquid fuels, distillation and extraction products thereof, into valuable liquids which comprises treating them with hydrogen and a catalyst containing molybdenum and heat at a temperature sufficient to promote the conversion at a pressure of at least 20 atmospheres.
7. The process of converting carbonaceous substances, such as solid and liquid fuels, distillation and extraction products thereof, into valuable liquids which comprises treating them with hydrogen under increased pressure of the order of 200 to 800 atmospheres at temperatures of the order of 400 to 550° C. while confined in a vessel of adequate strength the surfaces of which exposed to the reacting materials have a degree of resistance to attack by hydrogen and sulphur, under the conditions of temperature and pressure given and in the presence of the reaction products, not substantially less than that of an alloy of iron containing 10 percent of chromium and .2 percent of carbon.
8. A process for converting carbonaceous substances such as solid and liquid fuels, distillation and extraction products thereof, into valuable liquids by destructive hydrogenation in a reaction vessel the inner surface of which comprises chromium at a pressure of at least 20 atmospheres.
9. A process for converting carbonaceous substances such as solid and liquid fuels, distillation and extraction products thereof, into valuable liquids by destructive hydrogenation in a reaction vessel the inner surface of which is made of an alloy of chromium at a pressure of at least 20 atmospheres.
10. A process for converting carbonaceous substances such as solid and liquid fuels, distillation and extraction products thereof, into valuable liquids by destructive hydroge-
- tion in a reaction vessel the inner surface of which is made of an alloy containing at least 10 per cent of chromium at a pressure of at least 20 atmospheres.
11. The process for converting carbonaceous substances, such as solid and liquid fuels, distillation and extraction products thereof, into valuable liquids by destructive hydrogenation in a reaction vessel, the inner surface of which is made of an alloy of iron containing at least 10 percent of chromium and not more than .3 percent of carbon.
12. The process of converting carbonaceous substances, such as solid and liquid fuels, distillation and extraction products thereof, into valuable liquids which comprises employing hydrogen and an oxid of carbon and an added catalyst capable of combining hydrogen and the oxid of carbon to methanol and heat at a temperature sufficient to promote the conversion and at an elevated pressure of at least twenty atmospheres.
13. The process of destructively hydrogenizing carbonaceous substances, such as solid and liquid fuels, distillation and extraction products thereof, into valuable liquids which comprises treating them with hydrogen and a catalyst immune to sulfur poisoning, in the presence of a substantial amount of water, and heat at a temperature sufficiently high for the conversion and at a pressure of at least 20 atmospheres.
14. The process of converting carbonaceous substances, such as solid and liquid fuels, distillation and extraction products thereof, into valuable liquids, which comprises treating them with added hydrogen in the presence of an added solid catalyst immune to sulphur poisoning, and heat at a temperature of between about 300° and 700° C. and at a pressure of at least 20 atmospheres.
15. The process of converting carbonaceous substances, such as solid and liquid fuels, distillation and extraction products thereof, into valuable liquids, which comprises treating them with added hydrogen in the presence of an added catalyst immune to sulphur poisoning, and heat at a temperature of between about 300° and 700° C. and at a pressure of at least 20 atmospheres, the conditions of working, such as temperature, pressure and efficiency of the catalyst, being so adapted to each other as to give rise to the formation of substantial amounts of low boiling hydrocarbons of a gasoline character.
16. The process of converting carbonaceous substances, such as solid and liquid fuels, distillation and extraction products thereof into valuable liquids, which comprises treating them with added hydrogen and an added catalyst immune to sulphur poisoning, and heat at a temperature of between about 300° and 700° C. and at an elevated pressure of at least 100 atmospheres.

17. The process of converting carbonaceous substances, such as solid and liquid fuels, distillation and extraction products thereof into valuable liquids, which comprises treating them with a stream of hydrogen and an added catalyst immune to sulphur poisoning, and heat at a temperature of between about 300° and 700° C. and at an elevated pressure of at least 20 atmospheres. 70
18. The process of converting carbonaceous substances, such as solid and liquid fuels, distillation and extraction products thereof, into valuable liquids, which comprises treating them with added hydrogen and a catalyst comprising a metal of the sixth group of the periodic system and heat at a temperature of between about 300° and 700° C. and at a pressure of at least 20 atmospheres. 75
19. The process of converting carbonaceous substances, such as solid and liquid fuels, distillation and extraction products thereof, into valuable liquids, which comprises treating them with a stream of hydrogen and a catalyst containing a metal of the sixth group of the periodic system and heat at a temperature of between about 300° and 700° C. and at an elevated pressure upwards of 100 atmospheres. 80
20. The process of converting carbonaceous substances, such as solid and liquid fuels, distillation and extraction products thereof, into valuable liquids, which comprises treating them with hydrogen and a catalyst containing molybdenum, and heat at a temperature of between about 300° and 700° C. and at a pressure of at least 20 atmospheres. 85
21. The process of converting carbonaceous substances, such as solid and liquid fuels, distillation and extraction products thereof, into valuable liquids, which comprises treating them with hydrogen and a catalyst containing molybdenum, and heat at a temperature of between about 300° and 700° C. and at a pressure of more than 50 atmospheres. 90
22. The process of converting carbonaceous substances, such as solid and liquid fuels, distillation and extraction products thereof, into valuable liquids, which comprises treating them with hydrogen in a stream, and a catalyst containing molybdenum, and heat at a temperature of between about 300° and 700° C. and at an elevated pressure upwards of 100 atmospheres. 100
23. The process of converting carbonaceous substances, such as solid and liquid fuels, distillation and extraction products thereof, into valuable liquids, which comprises treating them with hydrogen and more than one catalyst immune to sulphur poisoning, and heat at a temperature of between about 300° and 700° C. and at a pressure of at least 20 atmospheres. 105
24. The process of converting carbonaceous substances, such as solid and liquid fuels, distillation and extraction products thereof into valuable liquids, which comprises first treating them with hydrogen at a pressure of at least 20 atmospheres and 110
- thereof, into valuable liquids, which comprises treating them with hydrogen and a catalyst immune to sulphur poisoning, in the presence of a substantial amount of water, and heat at a temperature of between about 300° and 700° C. and at a pressure of at least 50 atmospheres. 115
25. The process of producing liquids from solid fuel materials which comprises destructively hydrogenating the initial material in the presence of an added catalyst immune to sulphur poisoning at a pressure of at least 20 atmospheres and at a temperature of between about 300° and 700° C. 120
26. The process of producing liquid hydrocarbons from coaly material which comprises destructively hydrogenating the initial material in the presence of an added catalyst immune to sulphur poisoning at a pressure of at least 20 atmospheres and at a temperature of between about 300° and 700° C. 125
27. The process of producing liquid hydrocarbons from lignite which comprises destructively hydrogenating the initial material in the presence of an added catalyst immune to sulphur poisoning at a pressure of at least 20 atmospheres and at a temperature of between about 300° and 700° C. 130
28. The process of converting carbonaceous substances, such as solid and liquid fuels, distillation and extraction products thereof, into valuable liquids, which comprises treating them with hydrogen and a catalyst containing a metal of the sixth group of the periodic system, and heat at a temperature of between about 300° and 700° C. and at an elevated pressure of at least 50 atmospheres. 135
29. The process of converting carbonaceous substances, such as solid and liquid fuels, distillation and extraction products thereof, into valuable liquids, which comprises treating them with a continuous stream of hydrogen and a substantial amount of water and heat at a temperature of between about 300° and 700° C. and at a pressure of at least 50 atmospheres in the presence of a catalyst immune to poisoning by sulphur. 140
30. The process of converting carbonaceous substances, such as solid and liquid fuels, distillation and extraction products thereof into valuable liquid products, which comprises treating a mixture of a solid fuel of a more recent geological age than coal with another carbonaceous material by destructive hydrogenation in the presence of a catalyst immune to sulphur poisoning under a pressure of at least 20 atmospheres and at a temperature between about 300° and 700° C. 145
31. The process of destructively hydrogenizing carbonaceous substances, such as solid and liquid fuels, distillation and extraction products thereof into valuable liquids, which comprises first treating them with hydrogen at a pressure of at least 20 atmospheres and 150

with heat at a temperature sufficient to promote the conversion until products poor in fractions of low boiling point are obtained, and then in a further stage converting the 5 heavier fractions of such products alone into products rich in fractions of low boiling point by a further treatment with hydrogen at a pressure of at least 20 atmospheres and heat at a temperature sufficient to promote 10 the conversion, in the presence of an added catalyst immune to sulphur poisoning.

32. The process of destructively hydrogenizing carbonaceous substances, such as solid and liquid fuels, distillation and extraction 15 products thereof into valuable liquids, which comprises first treating them with a current of hydrogen at a pressure of at least 50 atmospheres and with heat at a temperature sufficient to promote the conversion until 20 products poor in fractions of low boiling point are obtained, and then in a further stage converting the heavier fractions of such products alone into products rich in fractions of low boiling point by a further treatment with hydrogen at a pressure of at least 50 atmospheres and heat at a temperature sufficient to promote the conversion in the 25 presence of an added catalyst immune to sulphur poisoning.

33. The process of converting carbonaceous substances, such as solid and liquid fuels, distillation and extraction products thereof into valuable liquids, which comprises first treating them with a current of 30 hydrogen at a pressure of at least 50 atmospheres and with heat at a temperature of between about 300° and 700° C. until tar-like products poor in fractions of low boiling point are obtained, and then in a further 40 stage converting the tar-like products alone into products rich in fractions of low boiling point by a further treatment with hydrogen at a pressure of at least 50 atmospheres and heat at a temperature of between about 300° 45 and 700° C. and in the presence of a catalyst.

34. The process of destructively hydrogenizing carbonaceous substance, such as solid and liquid fuels, distillation and extraction products thereof, into valuable liquids which 50 comprises treating them with hydrogen in the presence of an added solid catalyst immune to sulphur poisoning, at a temperature sufficiently high for the conversion and at a pressure of at least 20 atmospheres for a period such that, under the conditions as above 55 given, the product is substantially free from asphalt.

35. The process of destructively hydrogenizing carbonaceous substances such as solid 60 and liquid fuels, distillation and extraction products thereof, containing asphaltic hydrocarbons, into valuable liquids, which comprises treating them with hydrogen in the presence of an added solid catalyst immune 65 to sulphur poisoning, at a temperature suf-

ficiently high for the conversion and at a pressure upwards of 100 atmospheres for a period such that, under the conditions as above given, the product is substantially free from asphalt.

70

36. The process of converting carbonaceous substances such as solid and liquid fuels, distillation and extraction products thereof, into valuable liquids which comprises continuously feeding said substances with hydrogen into a reaction space containing a solid catalyst immune to sulphur poisoning and held at a temperature of between about 300 and 700° C. while maintaining a pressure of at least 20 atmospheres in said space and 80 continuously removing resulting products.

75

37. The process of destructively hydrogenizing carbonaceous substances such as solid and liquid fuels, distillation and extraction products thereof, into valuable liquids which comprises treating them with a stream of hydrogen in the presence of an added solid catalyst immune to sulphur poisoning, and heat at a temperature sufficiently high for the conversion and at a pressure of at least 20 atmospheres and carrying off resulting products in the stream of hydrogen.

85

38. The process of converting carbonaceous substances such as solid and liquid fuels, distillation and extraction products thereof, into valuable liquids which comprises treating them with a stream of hydrogen in the presence of an added solid catalyst immune to sulphur poisoning, and heat at a temperature of between about 300° and 700° 90 C. and at a pressure of at least 20 atmospheres and carrying off resulting products in the vapor state in the stream of hydrogen.

90

39. The process of destructively hydrogenizing carbonaceous substances such as solid and liquid fuels, distillation and extraction products thereof, into valuable liquids which comprises treating them with a stream of hydrogen in the presence of an added solid catalyst immune to sulphur poisoning, and heat at a temperature sufficiently high for the conversion and at a pressure of at least 20 atmospheres, carrying off resulting products in the vapor state in the stream of hydrogen and cooling the mixed vapors 105 whereby the liquefiable portions of the said products are substantially completely removed from the hydrogen.

110

40. The process of destructively hydrogenizing carbonaceous substances, such as solid and liquid fuels, distillation and extraction products thereof, into valuable liquids which comprises treating them with a stream of hydrogen in the presence of an added solid catalyst immune to sulphur 120 poisoning, and heat at a temperature sufficiently high for the conversion and at a pressure of at least about 200 atmospheres, carrying off the resulting products in the vapor state in the stream of hydrogen, cool- 125

115

120

125

130

ing the mixed vapors, whereby normally liquid products are separated, removing gaseous hydrocarbons from the stream of hydrogen and returning the hydrogen to the reaction zone.

41. The process of destructively hydrogenizing carbonaceous substances, such as solid and liquid fuels, distillation and extraction products thereof, into valuable liquids which comprises continuously feeding the said substances with hydrogen into a reaction space containing a solid catalyst immune to sulphur poisoning and held at a temperature sufficiently high for the conversion while maintaining a pressure of at least 20 atmospheres in said space, the conditions as above given being adjusted to permit of continuously removing resulting products substantially free from asphalt.

42. The process of converting carbonaceous substances such as solid and liquid fuels, distillation and extraction products thereof, containing asphaltic hydrocarbons, into valuable liquids which comprises continuously feeding the said substances with hydrogen into a reaction space containing a solid catalyst immune to sulphur poisoning and held at a temperature of between about 300° and 700° C. while maintaining a pressure of at least 200 atmospheres in said space, the conditions as above given being adjusted to permit of continuously removing resulting products substantially free from asphaltic hydrocarbons.

43. The process of destructively hydrogenizing carbonaceous substances, such as solid and liquid fuels, distillation and extraction products thereof, into valuable liquids which comprises treating them with a stream of hydrogen in the presence of an added solid catalyst immune to sulphur poisoning, and heat at a temperature sufficiently high for the conversion and at a pressure of at least 20 atmospheres and carrying off resulting products substantially free from asphalt in the stream of hydrogen.

44. The process of converting carbonaceous substances, such as solid and liquid fuels, distillation and extraction products thereof, into valuable liquids which comprises treating them with a stream of hydrogen in the presence of an added solid catalyst immune to sulphur poisoning, and heat at a temperature of between about 300° and 700° C. and at a pressure of at least 20 atmospheres, the conditions as above given being adjusted to permit of continuous withdrawal of reaction products substantially free from asphalt, withdrawing such products admixed with the hydrogen stream, separating the reaction product from the hydrogen and returning the hydrogen to the reaction zone.

45. The process of converting carbonaceous substances, such as solid and liquid fuels, distillation and extraction products thereof, into

valuable liquids which comprises treating them with added hydrogen and a catalyst comprising a compound of a metal of the sixth group of the periodic system and heat at a temperature between about 300° and 700° C. and at a pressure of at least 20 atmospheres.

46. The process of converting carbonaceous substances, such as solid and liquid fuels, distillation and extraction products thereof, into valuable liquids which comprises continuously feeding said substances with hydrogen into a reaction space containing a compound of a metal of the sixth group of the periodic system and held at a temperature between about 300° and 700° C. while maintaining a pressure of at least 50 atmospheres in said space and continuously removing products of the reaction.

47. The process of converting carbonaceous substances, such as solid and liquid fuels, distillation and extraction products thereof, into valuable liquids which comprises treating them with added hydrogen and a catalyst comprising an oxide of a metal of the sixth group of the periodic system and heat at a temperature between about 300° and 700° C. and at a pressure of at least 20 atmospheres.

48. The process of converting carbonaceous substances, such as solid and liquid fuels, distillation and extraction products thereof, into valuable liquids which comprises continuously feeding said substances with hydrogen into a reaction space containing an oxide of a metal of the sixth group of the periodic system and held at a temperature between about 300° and 700° C. while maintaining a pressure of at least 50 atmospheres in said space and continuously removing products of the reaction.

49. The process of converting carbonaceous substances, such as solid and liquid fuels, distillation and extraction products thereof, into valuable liquids which comprises treating them with added hydrogen and a catalyst comprising a compound of molybdenum and heat at a temperature between about 300° and 700° C. and at a pressure of at least 20 atmospheres.

50. The process of converting carbonaceous substances, such as solid and liquid fuels, distillation and extraction products thereof, into valuable liquids which comprises continuously feeding said substances with hydrogen into a reaction space containing a compound of molybdenum and held at a temperature between about 300° and 700° C. while maintaining a pressure of at least 50 atmospheres in said space and continuously removing products of the reaction.

51. The process of converting carbonaceous substances, such as solid and liquid fuels, distillation and extraction products thereof, into valuable liquids which comprises treat-

ing them with added hydrogen and a catalyst comprising molybdenum oxide and heat at a temperature between about 300° and 700° C. and at a pressure of at least 20 atmospheres.

52. The process of converting carbonaceous substances, such as solid and liquid fuels, distillation and extraction products thereof, into valuable liquids which comprises continuously feeding said substances with hydrogen into a reaction space containing molybdenum oxide and held at a temperature between about 300° and 700° C. while maintaining a pressure of at least 50 atmospheres in said space and continuously removing products of the reaction.

53. The process of converting carbonaceous substances, such as solid and liquid fuels, distillation and extraction products thereof, into valuable liquids which comprises treating them with added hydrogen and a catalyst comprising a compound of chromium and heat at a temperature between about 300° and 700° C. and at a pressure of at least 20 atmospheres.

54. The process of converting carbonaceous substances, such as solid and liquid fuels, distillation and extraction products thereof, into valuable liquids which comprises continuously feeding said substances with hydrogen into a reaction space containing a compound of chromium and held at a temperature between about 300° and 700° C. while maintaining a pressure of at least 50 atmospheres in said space and continuously removing products of the reaction.

55. The process of converting carbonaceous substances, such as solid and liquid fuels, distillation and extraction products thereof, into valuable liquids which comprises treating them with added hydrogen and a catalyst comprising chromium oxide and heat at a temperature between about 300° and 700° C. and a pressure of at least 20 atmospheres.

56. The process of converting carbonaceous substances, such as solid and liquid fuels, distillation and extraction products thereof, into valuable liquids which comprises continuously feeding said substances with hydrogen into a reaction space containing chromium oxide and held at a temperature between about 300° and 700° C. while maintaining a pressure of at least 50 atmospheres in said space and continuously removing products of the reaction.

57. The process of converting carbonaceous substances, such as solid and liquid fuels, distillation and extraction products thereof, into valuable liquids which comprises treating them with added hydrogen and a catalyst comprising a compound of tungsten and heat at a temperature between about 300° and 700° C. and at a pressure of at least 20 atmospheres.

58. The process of converting carbona-

ceous substances, such as solid and liquid fuels, distillation and extraction products thereof, into valuable liquids which comprises continuously feeding said substances with hydrogen into a reaction space containing a compound of tungsten and held at a temperature between about 300° and 700° C. while maintaining a pressure of at least 50 atmospheres in said space and continuously removing products of the reaction.

59. The process of converting carbonaceous substances, such as solid and liquid fuels, distillation and extraction products thereof, into valuable liquids which comprises treating them with added hydrogen and a catalyst comprising tungsten oxide and heat at a temperature between about 300° and 700° C. and at a pressure of at least 20 atmospheres.

60. The process of converting carbonaceous substances, such as solid and liquid fuels, distillation and extraction products thereof, into valuable liquids which comprises continuously feeding said substances with hydrogen into a reaction space containing tungsten oxide and held at a temperature between about 300° and 700° C. while maintaining a pressure of at least 50 atmospheres in said space and continuously removing products of the reaction.

In testimony whereof we have hereunto set our hands.

CARL KRAUCH.
